unit housing 48. By moving the manipulating handle 63 of the lever 58 inwardly towards the printing cylinder, the motor unit housing 48 is rocked to move the grooved pulley 51 from engagement with the rim of the index wheel 47, thus releasing the wheel for manual operation when desired. When the lever 58 is drawn outwardly, the motor unit housing is rocked to move the grooved pulley 51 back into engagement with the rim 46 of the index wheel, and it is held firmly in engagement therewith by gravity, inasmuch as, in this position the center of gravity of the motor unit has passed to one side of a vertical plane passing through its pivotal stud 56.

The supporting uprights 21 positioned at opposed ends of the machine frame have brackets 65 secured thereto, and these brackets support a composite carrier, which, in turn, movably supports a squeegee roller and water box or fluid containing receptacle to be hereinafter referred to. The carrier includes spaced inner arms 66 pivotally secured to the bracket 65, as indicated at 67, and the outer terminal of each arm 66 is pivotally secured to an offset bearing head 68, formed on the inner terminal of an outer arm 70 by means of a stud 71, which is threadedly secured to the bearing head 68 and extends through a sleeve or bushing 72 on which the pivotal bearing surface or bore 73 of the outer end of the arms 66 is mounted, as best shown in Figure 9. The bushing 72 also rotatably supports an idler sprocket 75, to be hereinafter referred to, and a limited degree of turning motion of each outer arm 70 relative to its inner arm 66 about its stud 71 is permitted by the pin and slot arrangement indicated at 74. Each bearing head 68 is provided with a shouldered recess 76 in axial alignment with the stud 71 for the reception of antifriction bearings 77 which rotatably support a pressure or squeegee roller 78, the function of which is to be hereinafter disclosed. A bracket arm 80 is secured to each outer arm 70, by screws or other securing devices 81, and the outer terminal of each bracket 80 is pivotally secured to a link 82, as indicated at 83, and the opposed terminal of each link is pivotally secured to the bracket 65, as indicated at 85. Thus it will be seen that as the inner arms 66 are moved about their pivots 67 the links 82 will serve to maintain the outer arms 70 in substantially horizontal position.

In order to raise and lower the composite carrier, which includes the inner arms 66, outer arms 70 and links 82, a hand wheel 86 is rotatably mounted on a shaft or stud 87 secured to the upright 21 of the machine frame, and a sprocket 88 is secured to rotate with the hand wheel 86. This sprocket drives or rotates a larger sprocket 89 through a chain 90 which is trained over both sprockets, and the large sprocket 89 is keyed to a shaft 91, which extends across the machine and is journaled in the upper terminals of the uprights 21, as indicated at 92. Drive sprockets 93 are keyed at each side of the machine to the shaft 91, and lifting chains 95 having their outer terminals secured to the uprights 21, as indicated at 96, are trained around the idler sprockets 75 and over the drive sprockets 93 to raise and lower the composite water box carrier, as will be more fully disclosed herein-after, and the chains 95 after passing over the drive sprockets 93 are suspended loosely at the side of the machine, as shown in Figure 2.

The outer terminal of each outer arm 70 is pro-

vided with a bearing aperture 97 in which a shaft 98 is rotatably supported, and this shaft extends across the machine, and, in turn, supports depending links or hangers 100 which are keyed or otherwise secured to the shaft 98. The outer or lower terminal of each link 100 is pivotally secured to the frame 101 of a fluid containing receptacle or water box 102, as indicated at 103. A bar or supporting leg 105 is pivotally secured to each end of the water box 102, as indicated at 106, and the outer terminal of each leg has a roller 107 secured thereto, and each roller is received within a channeled supporting rail or track 108 depending from each arm 70. The intermediate portion of each leg or bar 105 is provided with an elongated aperture or slot 110 for the reception of a stud 111 which is secured to and extends from the water box into the slot 110 to permit a slight movement between the water box 102 and the legs or bars 105 to permit the box to "float", as will be more fully disclosed hereinafter. A fixed clutch member 112 having a recess 113 is secured to the outer terminal of the arm 70, and a cooperating clutch member 115, having extensions 116, is keyed to the shaft 98 for sliding movement thereon, and this clutch member 115 is stressed or biased toward the clutch member 112 by a suitable spring 117. The clutch mechanism is operated by a shaft or rod 118, which is rotatably received within the bore 120 or aperture 120 formed in the fixed clutch member 112, and it is provided with a flat face 121 which engages a flat face or end of the movable clutch member 115. An operating handle 122 extends perpendicularly from the clutch rod 118, and by turning this handle through an arc, the flat face 121 of the clutch rod 118 engages the flat end of the movable clutch 115 thus moving the extension 116 of the movable clutch from the recess 113 of the fixed clutch, thereby permitting free rotation of the movable clutch 115, shaft 98, consequently permitting movement of the links 100 and suspended water box 102.

The water box or fluid containing receptacle 102 includes an elongated chamber 123, the length of which is substantially the length of the printing cylinder 28. A cover member 125 is secured to the water box and is provided with vent apertures 126 preferably positioned at the end of the box which is disposed away from the printing cylinder, and a partition 127 extends from the cover 125 into the chamber, and this partition is preferably positioned towards the end of the chamber which is disposed toward the printing cylinder. An outlet neck 128 is provided on the water box in which a series of inclined outlet apertures 130 are drilled. A bakelite plate or strip 131 is secured to the lower portion of the outlet neck 128, and an inclined brass plate 132 is slidably secured to the inclined portion of the cover member 125 which overhangs the outlet neck 128, by means of screws or other securing devices 133, which extend through elongated slots 135 formed in the brass plate 132, and are secured to the inclined portion of the cover member 125. The outer terminals or throat portions of the lower bakelite plate 131 and the upper sliding plate 132 are tapered to present a narrow outlet terminal to be received within the space formed between the squeegee roller and printing cylinder near the line on which these members engage each other, and the tapered outer terminals of these plates engage each other when the sliding plate is in its outermost position to

close the outlet of the water box, thereby presenting a valve arrangement capable of discharging a film of water in a line on the printing cylinder periphery when the sliding plate is moved to open position.

In order to slide the inclined plate 132 to open and closed positions, a manipulating handle or bar 136 is provided which is pivotally secured at its opposed terminals to bell crank levers 137 which have their intermediate portion pivotally secured to a bracket 138, carried by the water box cover 125, by shoulder screws or other securing devices 140, and the terminals of the bell cranks 137 which are remote from the manipulating bar 136 are pivotally secured to channeled blocks 141, as indicated at 142. The channel or elongated recess 143 of each block 142 fits over a rectangular bar 145 secured to the inclined valve plate 132 and extends longitudinally thereof, thereby permitting the blocks 141 to slide along the bar 145 when the manipulating handle 136 is moved to open and close the valve plate 132.

Water or other suitable fluid is conveyed to the water box through a flexible hose or conduit 146 which leads to an inlet valve or cock 147 that communicates with the chamber of the water box. Outlet couplings 148 are secured to the opposed ends of the water box and communicate with the chamber and also with flexible outlet conduits 150, and these outlet couplings communicate with the chamber of the water box at a level above the point where the outlet apertures 130 communicate with the water box chamber and also above the lower terminal of the partition 127, for reasons to be hereinafter disclosed.

To permit the design or image to be etched into the cylinder while in the machine, a basin or tray 151 is supported by the machine frame 15 below the printing cylinder 28 and extends throughout the length of the cylinder. The tray 151 is lined with rubber or other acid resisting material 152, and a flexible drain hose or conduit 153 communicates with the lowest portion of the tray bottom and this hose normally leads to a drain opening 16 formed in the drain basin 17, or, if preferred, the hose may be bent to one side of the machine frame to convey the etching acids into a suitable receptacle, not shown, in the event the acids are to be preserved for subsequent use. A hood 155 is supported above the printing cylinder by the upright 21, and this hood is provided with a suitable outlet flue 156.

In the operation of the machine, a printing cylinder is conveyed to the machine by a crane or other suitable conveyance, not shown, and lowered onto the supporting rails 20, as indicated in dotted lines in Figure 1. It is then moved into the open hinged working bearings and the hinged portions 25 of the bearings are then closed to rotatably support the cylinder on the machine frame, and the hand wheel 32 manipulated to force the cylinder into correct longitudinal position. The suitable register marks are then inscribed on the peripheral portion of the cylinder, as hereinbefore disclosed and also disclosed in the Springstead Patent No. 1,832,255. The means for locking the marking stylus and components in desired registered position has also been hereinbefore referred to and disclosed in the Springstead patent and co-pending Harry Little application for Registering mechanism, filed March 7, 1935, Serial No. 9,865. The sensitized

carbon sheet is also provided with suitable registering marks on the margin thereof, and when registering the carbon sheet "S" on the cylinder the leading edge of the sheet is brought into alignment with register marks on the cylinder and is secured in place on the peripheral portion of the cylinder by means of gummed tape or other suitable adhesive 155, as best shown in Figure 10. During this part of the operation, the water box 102 is swung back away from the printing cylinder 28 by first releasing the clutch 115 and gripping the handle 104 of the water box to move the supporting rollers 107 along the rail 108 and to swing the supporting links 100 about their supporting shaft 98, thus positioning the box as indicated in full lines in Figure 10. The roller 78 is raised slightly off the cylinder, thus permitting convenient access to the cylinder from both sides of the machine, and the cylinder is turned by hand and the entire sheet is pressed into contact with its peripheral portion. The rearmost end of the sheet is then also secured to the cylinder periphery by an adhesive and the cylinder rotated several times to insure that the sheet is correctly registered and in proper place. Now the cylinder is turned to bring the forward or leading edge of the sheet uppermost, and the squeegee roller 78 brought down to hold it in place. The rear edge of the sheet is then loosened from the cylinder and turned backward and upward and led over the roller 78, as shown in Figure 5, with the greater portions of the sheet then hanging to the right of the roller.

In the squeegeeing operation, the handle 63 is manipulated to swing the motor unit so that its grooved pulley 51 engages the rim 46 of the index wheel 47 to thereby rotate the printing cylinder 28. The water box which has been filled, by manipulating the inlet cock 147, with water or other suitable fluid to the level permitted by the outlets 148, as shown in Figure 5, is moved by manipulating the hand wheel 86 thus causing the sprockets 88, 89 and chain 90 to rotate the drive sprocket 93, thus feeding out the supporting chain 95 around the idler sprockets 75 to permit the composite carrier to lower the water box so that it may be moved along its guide rail 108 to the position indicated in Figure 5 with the tapered outlet terminals of the plates 131 and 132 positioned immediately adjacent the line on which the squeegee roller 78 engages the peripheral surface of the printing cylinder 28. The bar 136 is manipulated to slide the valve plate 132 away from the printing cylinder and squeegee roller to deposit a film of water on a line near the line where the squeegee roller engages the carbon sheet on the printing cylinder immediately the cylinder is rotated. After a sufficient quantity of water has been supplied to the peripheral portion of the cylinder the manipulating bar 136 is moved to slide the valve plate 132 to closed position, thus shutting off the supply of water or fluid. As the printing cylinder 28 and squeegee roller 78 continue to rotate, the water is crowded ahead of the contact line of these two rollers, thereby wetting the cylinder surface and the sensitive side of the carbon sheet as they come together and leaving the opposed or backing side entirely dry, and the pressure of the squeegee roller effects perfect contact of the entire sheet with the peripheral surface of the cylinder. It is necessary that the water supplied to the printing cylinder and carbon tissue be deposited on a line and in a uniform film free of bubbles, and this is made possible by the provision of the partition 75

MECHANISM AND METHOD OF MARKING, SQUEEGEEING, AND DEVELOPING PRINT- ING CYLINDERS

Gustave A. Friess, Rye Township, Westchester
County, N. Y., assignor to R. Hoe & Co. Inc.,
New York, N. Y., a corporation of New York

Application July 12, 1935, Serial No. 31,082

24 Claims. (Cl. 101—34)

This invention relates to marking, squeegeeing or rotogravure printing cylinders, and particularly to the method and mechanism for applying and securing sensitized carbon tissue in accurately registered position upon the peripheral portion of the printing cylinder to permit the design or image to be etched thereon for rotogravure printing.

10 Accurate register is essential in rotary rotogravure printing, especially multi-color rotary rotogravure printing, wherein a number of separate impressions in different colors are usually made. A separate cylinder is employed for each color and the images that are etched on the several cylinders must be located very accurately in order to insure proper register in printing. In the preparation of the form cylinders for rotogravure printing, the form for each page is printed on a sheet of sensitized tissue from which it is transferred to the surface of the form cylinder and subsequently etched into the cylinder surface. Register marks are drawn on the tissue sheet on the margin space, and a marking machine is provided for marking circumferential and longitudinal lines on the peripheral surface of the cylinder, and when the register marks on the tissue sheets are aligned with the marks on the cylinder surface, the tissue sheets are then correctly positioned to insure that the images are transferred therefrom to the printing cylinder surface to produce accurately registered printing.

After a portion of the sensitized carbon sheet or tissue has been aligned with register marks on the printing cylinder, it is then necessary to secure the entire sheet in accurately registered positions upon the cylinder, and to treat the carbon tissue so that its usual supporting back may be stripped therefrom to leave the sensitized image bearing carbon tissue on the cylinder surface preparatory to the usual etching operation. Therefore, an object of this invention is to provide improved means and method for securing sensitized tissue sheet in accurate register upon the printing surface of the cylinder and for treating the tissue sheet to permit the ready removal of its flexible backing.

Another object of this invention is to provide improved means and method for applying the sensitized tissue to the peripheral surface of the printing cylinder, and for conveying fluid along a line on the cylinder and tissue to aid in the application of the tissue to the cylinder and in the ready removal of the flexible backing from the carbon tissue.

A further object of my present invention is to provide means for holding a portion of a sensitized carbon tissue upon the peripheral portion of the printing cylinder and for supporting the remainder of the tissue away from the cylinder and for conveying fluid to the cylinder and to the inner side of the carbon tissue.

An additional object of this invention is to provide a machine for rotatably supporting a printing cylinder and incorporating means for clamping the leading edge of a carbon tissue upon the periphery of the cylinder, applying fluid in a line on the periphery of the cylinder and to the tissue, and for rolling the fluid treated tissue to secure it in registered position upon the peripheral portion of the cylinder.

Another object of the present invention is to provide a marking, squeegeeing and developing machine for rotogravure printing cylinders having a movably supported roller and fluid containing receptacle, the roller co-operating with the cylinder to grip the leading edge of a sensitized tissue sheet in accurate register upon the cylinder surface, also supports the sheet away from the cylinder and rotates in engagement with the tissue sheet and the cylinder to roll the sheet on the cylinder to secure it thereon in accurately registered position, and means for conveying fluid from the receptacle along a line on the surface of the printing cylinder near the line on which the roller engages the tissue positioned on the cylinder to thereby wet the tissue to aid its adhesion to the cylinder surface and to permit the ready removal of its flexible backing.

It is also an object of this invention to provide a marking, squeegeeing and developing machine for rotogravure printing cylinders of generally improved construction, whereby the device will be simple, durable and inexpensive in construction, as well as convenient, practical, servicable and efficient in its use.

With the foregoing and other objects in view, which will appear as the description proceeds, the invention resides in the combination and arrangement of parts, and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detailed description of an improved marking, squeegeeing and developing machine for rotogravure printing cylinders will now be given in

connection with the accompanying drawings forming a part of this specification, wherein:—

Figure 1 is an end elevation, parts broken away, of a combined marking, squeegeeing and developing machine having a photogravure printing cylinder rotatably mounted therein;

Figure 2 is an elevation taken in the same direction as Figure 1, but showing the upper portion of the machine;

Figure 3 is a plan view of the machine, parts appearing in section;

Figure 4 is a side elevation of the upper portion of the machine looking in the direction of arrow 4 of Figure 2, and depicting the carrier for the fluid receptacle;

Figure 5 is a fragmental vertical sectional view taken through the fluid receptacle or water box on the line 5—5 of Figure 6, and depicting the cooperative relationship of the water box, squeegee roller and printing cylinder;

Figure 6 is a plan view of the fluid receptacle or water box and components of the carrier therefor, the view being taken in the direction of arrow 6 of Figure 5;

Figure 7 is a fragmental plan view looking in the direction indicated by arrow 7 of Figure 2, and depicting the water box, squeegee roller and composite carrier therefor;

Figure 8 is a fragmental elevation depicting the slideable stylus or marker head employed in the machine;

Figure 9 is a fragmental sectional view taken on the line 9—9 of Figure 7, and illustrating the carrier and supporting bearing for the squeegee roller;

Figure 10 is an enlarged fragmental elevation of the outer portion of the carrier for supporting the water box and squeegee roller, and showing the cooperative relationship between the water box, squeegee roller and printing cylinder;

Figure 11 is a detailed plan view showing the registering or index plug employed in the machine;

Figure 12 is a transverse sectional view through the index plug taken on the line 12—12 of Figure 11; and

Figure 13 is a fragmental transverse sectional view taken through the operating portion of the clutch operating lever.

Referring to the drawings, in which similar reference characters designate corresponding parts, there is depicted an improved marking, squeegeeing and developing machine for rotogravure printing cylinders and having marking and registering mechanism of the type disclosed in Patent No. 1,832,255, granted November 17, 1931, to J. F. Springstead, and the co-pending application of Harry Little, filed March 7, 1935, Serial No. 9,865. The present machine includes

a frame 15, supported on a base 16 which is provided with a drain basin or receptacle 17, drain opening or outlet 18, and the frame 15 is provided with a printing cylinder supporting rail 20 and a superstructure in the form of supporting uprights 21. Bearing blocks 22 and 23 are supported at the opposed ends of the machine frame 15, and each bearing block is provided with a hinged section 25 to receive bearing members 26 supporting the shaft 27 of a rotogravure printing cylinder 28, and the outer or free end of each hinged section 25 is secured to the machine frame by suitable bolts or securing devices 30. The shaft 27 of the printing cylinder is provided with an annular shoulder 31, and a manipulating head 32 has a reduced stem which

is threaded into a slide 33, and the slide engages the end of the cylinder shaft 27 to force the shoulder 31 against its bearing 26, thereby holding the cylinder against longitudinal motion but permitting free rotation thereof. This cylinder supporting mechanism is well understood by those skilled in the art and is disclosed in the Springstead Patent No. 1,832,255.

In order to place suitable register marks on the peripheral surface of the printing cylinder 28, a rail 35 is supported by the machine frame and extends longitudinally thereof and parallel to the axis of the printing cylinder 28. This rail slidably supports a marker head or slide 36, which, in turn, supports a marker or stylus 37 which yieldingly engages the periphery of the cylinder. The marker head or slide is held in predetermined positions along the rail 35 by a spring pressed registering pin or plunger 38 operably supported by a sleeve 40 carried by the marker head or slide 36, and the registering pin engages the selected registering or index plug 41 suitably positioned along the rail. A bracket 42 secured to the machine frame also supports a similar spring pressed registering pin 43 which engages registering plugs 45, and these plugs 45 are spaced in predetermined positions around the rim 46 of an index or hand wheel 47 which is detachably secured to the shaft 26 of the printing cylinder 28 by a suitable key or other securing device to prevent rotation of the hand wheel relative to the printing cylinder 28. When the registering pin 43 snaps into engagement with the selected index plug 45, the index wheel 47 and printing cylinder 28 are held in predetermined angular position. Longitudinal register marks are produced on the peripheral surface of the printing cylinder by locking the index or hand wheel 47 in selected angular position, and sliding the marker slide 36 along the rail 35, thereby causing the stylus to produce a mark along the peripheral surface of the cylinder parallel to the axis thereof. Circumferential registering marks are inscribed around the peripheral surface of the printing cylinder 28 by locking the marker slide 36 in selected position along the rail 35 and withdrawing the registering pin 43 from engagement with the index plug 45 carried by the index wheel to permit the rotation of the index wheel and cylinder 28. As the cylinder rotates the stylus 37 will produce circumferential marks on the peripheral portion thereof. This marking and registering mechanism is disclosed in the Springstead Patent No. 1,832,255, and the co-pending Little application Serial No. 9,865 and therefore it is thought it requires no further elucidation in this application.

In order to drive the cylinder 28 and index wheel 47 by power, a composite motor unit is provided which includes a housing 48 which operably supports a constant speed fractional horse power motor 50 which is geared to a grooved pulley 51 through a conventional reducing gear 52 also operably supported by the housing 48. The housing 48 is provided with a bearing 53 mounted on the reduced end 55 of a stud 56 screwed or otherwise secured to the machine frame, as indicated at 57, thereby pivotally supporting the motor unit for moving the pulley 51 to and from engagement with the index wheel 47. A lever 58 is pivotally secured to the machine frame 15, as indicated at 60, and the opposed terminals of a link 61 are pivotally secured to the lever 58, and an arm 62 carried by the motor

127 which extends into the chamber of the water box below the water level permitted by the position of the outlets 148 so that any air that may be present in the chamber escapes through the 5 vent holes 126, thus causing the water which flows under the lower edge of the partition 121 through the series of outlet apertures 130 and through the restricted opening formed by the terminals of the sliding brass plate 132 and the 10 bakelite plate 131 to be entirely free of air bubbles. By providing the brass plate 132, corrosion is prevented, and the provision of the bakelite plate 131, provides means for engaging the peripheral 15 surface of the printing cylinder without scratching or marking the surface. The water box is guided in its movement towards the printing cylinder and squeegee rollers by the rollers 107 rolling along its rail or track 108 until the outer terminal of the bakelite plate 131 engages the peripheral portion of the cylinder. Further movement of the water box towards the line of contact between the printing cylinder and squeegee roller will cause the bakelite plate to ride up on the peripheral surface of the printing cylinder, 20 which floating action is permitted by the movement of the stud 111 in the slot 110. Thus it is seen that this action of the water box permits the outlet terminals of the fixed plate 131 and sliding plate 132 to be accurately positioned immediately adjacent the line of contact between the printing cylinder 28 and the squeegee roller 78, to accurately deposit a line of water immediately adjacent the line of contact. After the carbon sheet has been rolled to perfect contact with 25 the peripheral portion of the printing cylinder, the backing is stripped from the sensitive carbon tissue in the manner of removing backing from ordinary decalcomania, and then the cylinder is ready for etching, which is carried on in the 30 rubber lined tray 151 while the cylinder is still in the machine. The tray, being suitably lined and provided with a flexible drain permits the several solutions used during the etching and other treatment of the cylinder to be used in 35 succession, and the cylinder and tray washed between operations, or the solution or solutions, if preferred, may be preserved for future use by conveying them into suitable receptacles as hereinbefore described.

50 During the cylinder etching or treating operation, the escaping fumes may be collected in the hood 155 and conveyed away through the outlet flue 156.

What I claim is:

55 1. In a device of the class described, means for rotatably supporting a printing cylinder, a roller mounted to coact with the printing cylinder and to engage a sensitized tissue positioned on the peripheral surface of the cylinder, and means for conveying confined fluid to and depositing it on the peripheral surface of the cylinder and the sensitized tissue along a line near the line on which the roller engages the tissue on the cylinder.

60 2. In a device of the class described, means for rotatably supporting a printing cylinder, a roller mounted to coact with the printing cylinder and to engage a sensitized tissue positioned on the peripheral surface of the cylinder, and movable means for depositing fluid on the peripheral surface of the cylinder and the side of the sensitized tissue which is disposed towards the cylinder on a line near the line on which the 65 roller engages the tissue on the cylinder.

3. In a device of the class described, means for rotatably supporting a printing cylinder, a roller mounted to coact with the printing cylinder and to engage a sensitized tissue positioned on the peripheral surface of the cylinder, and movable 5 means for depositing confined fluid in a line on the peripheral portion of the cylinder and on the tissue near a point where a radial line passing through the axes of the cylinder and roller intersect the peripheral portion of the cylinder. 10

4. In a device of the class described, means for rotatably supporting a printing cylinder, a roller mounted to coact with the printing cylinder and to engage a sensitized tissue positioned on the peripheral surface of the cylinder, a movable 15 fluid containing receptacle, and means for conveying a film of fluid from the receptacle to the peripheral surface of the cylinder and the sensitized tissue along a line near the line on which the roller engages the tissue on the cylinder. 20

5. In a device of the class described, means for rotatably supporting a printing cylinder, a roller mounted to coact with the printing cylinder and to engage a sensitized tissue positioned on the peripheral surface of the cylinder, a fluid containing receptacle, means for movably supporting the receptacle and roller to permit movement thereof to and from the cylinder, and means for conveying a film of fluid from the receptacle directly to the peripheral surface of the cylinder 30 and the sensitized tissue along a line near the line on which the roller engages the tissue on the cylinder.

6. In a device of the class described, means for rotatably supporting a printing cylinder, a roller 35 mounted to coact with the printing cylinder and to engage a sensitized tissue positioned on the peripheral surface of the cylinder, a movable fluid containing receptacle, a converging throat extending from the receptacle and constructed 40 and arranged to convey a film of fluid from the receptacle directly to the peripheral surface of the cylinder and the sensitized tissue along a line near the line on which the roller engages the tissue on the cylinder. 45

7. In a device of the class described, means for rotatably supporting a printing cylinder, a roller mounted to coact with the printing cylinder and to engage a sensitized tissue positioned on the peripheral surface of the cylinder, movable 50 means for depositing a film of fluid on the peripheral surface of the cylinder and the sensitized tissue along a line near the line on which the roller engages the tissue on the cylinder, and manually operable means for controlling the 55 supply of fluid to the cylinder and the tissue.

8. In a device of the class described, means for rotatably supporting a printing cylinder, a roller mounted to coact with the printing cylinder and to engage a sensitized tissue positioned on the peripheral surface of the cylinder, a fluid containing receptacle, a converging throat extending from the receptacle and constructed and arranged to convey a film of fluid from the receptacle directly to the peripheral surface of the cylinder and the sensitized tissue along a line near the line on which the roller engages the tissue on the cylinder, and means for regulating the quantity of fluid supplied through the throat to the cylinder and tissue. 65 70

9. In a device of the class described, means for rotatably supporting a printing cylinder, a roller mounted to coact with the printing cylinder and to engage a sensitized tissue positioned on the peripheral surface of the cylinder, a mov- 75

able fluid containing receptacle, a converging throat extending from the receptacle and constructed and arranged to convey a film of fluid from the receptacle directly to the peripheral surface of the cylinder and the sensitized tissue along a line near the line on which the roller engages the tissue on the cylinder, and manually operable means for regulating the quantity of fluid supplied through the throat to the cylinder and tissue.

10. In a device of the class described, a frame, means for rotatably supporting a printing cylinder on the frame, a roller mounted to coact with the printing cylinder and to engage a sensitized tissue positioned on the peripheral surface of the cylinder, a movable receptacle, means supported by the frame for movably supporting the receptacle and roller to permit them to be moved towards and away from the cylinder, means for conveying fluid to the receptacle, and means for conveying fluid from the receptacle directly to the peripheral surface of the cylinder and the sensitized tissue along a line near the line on which the roller engages the tissue on the cylinder, and means for controlling the supply of fluid from the receptacle to the cylinder and the tissue.

11. In a device of the class described, a frame, means for rotatably supporting a printing cylinder on the frame, a roller to coact with the printing cylinder and to engage a sensitized tissue positioned on the peripheral surface of the cylinder, a movable receptacle, a carrier supported by the frame to support the receptacle and roller for movement towards and away from the cylinder, means for conveying fluid to the receptacle, and means for depositing fluid from the receptacle directly on the peripheral portion of the cylinder and on the tissue.

40. 12. In a device of the class described, a frame, means for rotatably supporting a printing cylinder on the frame, a roller to coact with the printing cylinder and to engage a sensitized tissue positioned on the peripheral surface of the cylinder, a movable receptacle, a carrier pivotally secured to the frame to support the receptacle and roller for movement towards and away from the cylinder, means for conveying fluid to the receptacle, and means for depositing fluid from the receptacle directly on the peripheral portion of the cylinder and on the tissue.

13. In a device of the class described, a frame, means for rotatably supporting a printing cylinder on the frame, a roller to coact with the printing cylinder and to engage a sensitized tissue positioned on the peripheral surface of the cylinder, a movable receptacle, a carrier pivotally secured to the frame to support the receptacle and roller for movement towards and away from the cylinder, manually operable means for moving the carrier to thereby move the receptacle and roller towards and away from the cylinder, and means for conveying fluid from the receptacle directly to the peripheral portion of the cylinder and to the tissue.

65. 14. In a device of the class described, a frame, means for rotatably supporting a printing cylinder on the frame, a movable receptacle for depositing fluid on the cylinder, a composite carrier supported by the frame and having separate components to support the receptacle for movement towards and away from the cylinder and in positions determined with relation to the cylinder.

75. 15. In a device of the class described, a frame,

means for rotatably supporting a printing cylinder on the frame, a movable receptacle for depositing fluid on the cylinder, a carrier supported by the frame to support the receptacle for movement towards and away from the cylinder, and separate supporting means for the receptacle carried by the carrier to permit movement of the receptacle relative to the carrier.

16. In a device of the class described, a frame, means for rotatably supporting a printing cylinder on the frame, a roller to coact with the printing cylinder and to engage a sensitized tissue positioned on the peripheral surface of the cylinder, a movable receptacle, a carrier pivotally secured to the frame to support the receptacle and roller for movement towards and away from the cylinder, manually operable means for moving the carrier to thereby move the receptacle and roller towards and away from the cylinder, supporting means for the receptacle carried by the carrier and constructed and arranged to permit movement of the receptacle relative to the carrier, and means for conveying fluid from the receptacle directly to the peripheral portion of the cylinder and to the tissue.

25. 17. In a device of the class described, a frame, means for rotatably supporting a printing cylinder on the frame, a roller to coact with the printing cylinder and to engage a sensitized tissue positioned on the peripheral surface of the cylinder, a movable receptacle, a carrier pivotally secured to the frame to support the receptacle and roller for movement towards and away from the cylinder, manually operable means for moving the carrier to thereby move the receptacle and roller towards and away from the cylinder, supporting means for the receptacle carried by the carrier and constructed and arranged to permit movement of the receptacle relative to the carrier, means for conveying fluid from the receptacle directly to the peripheral portion of the cylinder and to the tissue, and means for permitting floating movement of the receptacle to its supporting means.

40. 18. In a device of the class described, a frame, a roller to coact with the printing cylinder and to engage a sensitized tissue positioned on the peripheral surface of the cylinder, a movable receptacle, a carrier pivotally secured to the frame to support the receptacle and roller for movement towards and away from the cylinder, means for moving the carrier to move the roller and receptacle towards and away from the cylinder, means for supplying fluid to the receptacle, means for depositing fluid from the receptacle on the peripheral portion of the cylinder and on the tissue, and supporting means interposed between the carrier and receptacle and constructed and arranged to permit floating movement of the receptacle relative to the carrier so that the receptacle may position itself on the cylinder.

55. 19. In a device of the class described, a frame, means for rotatably supporting a printing cylinder on the frame, a roller coacting with the printing cylinder to engage a sensitized tissue positioned on the peripheral surface of the cylinder, a movable fluid containing receptacle, a carrier supporting the roller and receptacle and having separate components pivotally secured to the frame and to each other to move the roller and receptacle towards and away from the cylinder, a rail carried by one of the components of the carrier, means secured to the receptacle for engaging the rail to support and permit sliding movement of the receptacle relative to the car-

rier, separate supporting members pivotally secured to the carrier and receptacle to aid in supporting the receptacle, the receptacle being maintained in definite relation to the cylinder on the carrier when the carrier moves the receptacle directly and roller towards and away from the cylinder, means for permitting floating movement of the receptacle on its supporting means, and means for conveying fluid from the receptacle to the peripheral portion of the cylinder and to the tissue along a line near the line on which the roller engages the tissue on the cylinder.

20. In a device of the class described, a frame, means for rotatably supporting a printing cylinder on the frame, a roller coacting with the printing cylinder to engage a sensitized tissue positioned on the peripheral surface of the cylinder, a movable fluid containing receptacle, a carrier supporting the roller and receptacle and having separate components pivotally secured to the frame and to each other to move the roller and receptacle towards and away from the cylinder, manually operable means for moving the carrier towards and away from the cylinder, a rail carried by one of the components of the carrier, means secured to the receptacle for engaging the rail to support and permit sliding movement of the receptacle relative to the carrier, separate supporting members pivotally secured to the carrier and receptacle to aid in supporting the receptacle, the receptacle being maintained in definite relation to the cylinder on the carrier when the carrier moves the receptacle and roller towards and away from the cylinder, means for permitting floating movement of the receptacle relative to its supporting means, and means for conveying fluid from the receptacle to the peripheral portion of the cylinder and to the tissue.

21. The method of securing backed sensitized tissue to a printing cylinder, which consists in securing the leading edge of the tissue and backing sheet in registered position on the peripheral surface of the cylinder, gripping the leading edge of the tissue and backing sheet between the cylinder and a roller, depositing a determined quantity of fluid on the peripheral surface of the cylinder and tissue along a line near the line on which

the roller engages the tissue on the cylinder, and rotating the cylinder and roller to force the fluid ahead of the line on which the cylinder and roller engage the tissue thereby wetting one side of the tissue and pressing it on the peripheral surface of the cylinder to cause it to adhere thereto, and removing the backing sheet from the tissue thereby leaving the tissue in registered position on the peripheral surface of the cylinder.

22. The method of securing backed sensitized tissue to a printing cylinder, which consists in securing the leading edge of the tissue and backing sheet in registered position on the peripheral surface of the cylinder, gripping the leading edge of the tissue and backing sheet between the cylinder and a roller, removing the remainder of the tissue and backing sheet from the cylinder and supporting it on the roller, depositing fluid in a line on the peripheral surface of the cylinder and tissue near the line on which the roller engages the tissue on the cylinder, and rotating the cylinder and roller to force the fluid ahead of the line on which the cylinder and roller engage the tissue thereby wetting one side of the tissue and pressing it on the peripheral surface of the cylinder to cause it to adhere thereto, and removing the backing sheet from the tissue thereby leaving the tissue in registered position on the peripheral surface of the cylinder.

23. In a device of the class described, a frame, means for rotatably supporting a printing cylinder on the frame, means coacting with the cylinder to secure a sensitized tissue to the cylinder during the rotation of the cylinder, and a motor drive unit for rotating the cylinder, the entire motor unit being manually movable to and from cylinder operating positions.

24. In a device of the class described, a frame, means for rotatably supporting a printing cylinder on the frame, means coacting with the cylinder to secure a sensitized tissue to the cylinder during the rotation of the cylinder, manually operable means for rotating the cylinder, and power operating means bodily movable to operably engage the manually operable means to rotate the cylinder.
